UNITED STATES PATENT OFFICE.

JOHN A. DIENNER, OF CHICAGO, ILLINOIS.

VACUUM-FEED TANK.

Application filed October 29, 1933. Serial No. 671,281.

To all whom it may concern:

Be it known that I, JOHN A. DIENNER, a citizen of the United States, residing at Chicago, in the county of Cook and State of Illinois, have invented a certain new and useful Improvement in Vacuum-Feed Tanks, of which the following is a full, clear, concise, and exact description, reference being had to the accompanying drawings, forming a part of this specification.

My invention relates to vacuum tanks for fuel feeding systems and the like.

The present invention is an improvement upon the prior devices shown in my co-pending application, Serial No. 466,248, filed May 2, 1921. In that application I disclose and claim the fundamental idea of operating the main valve by a fluid pressure operated motor, which motor is controlled by certain pilot valves.

The present application discloses a structure in which there is but a single pilot control valve governed by a single float and a single main valve for controlling the operation of the entire device, that is, for admitting air to exhaust the pumping chamber and to discharge liquid fuel therefrom.

A further feature of novelty resides in the mounting of the float and pilot valve so as to assist the motor in its function of opening and closing the main valve in addition to performing its main function of closing and opening the pilot valve. My invention also makes possible the use of a relatively large air admission valve which may be opened in advance of the opening of the main valve, this valve serving as a relief valve to admit air in advance of opening the main valve which dumps the liquid fuel.

Further features of novelty reside in combinations of parts and details of construction which will be apparent from the following detailed description.

The fundamental object of the present invention is to provide a simple and inexpensive construction, together with reliability and durability. As an instance of this, I wish to point out that in the preferred form of my invention not a single spring is required, yet all of the operations of the valves are carried on with a snap and certainty by a combination of weight and pneumatic action.

In order to acquaint those skilled in the art with the manner of constructing and operating my invention, I shall now describe a

particular embodiment of the same in connection with the accompanying drawings in which,

Fig. 1 is a vertical sectional view of a form of tank embodying my invention;

Fig. 2 is a fragmentary sectional view of a modified form of pilot valve and sleeve to be mounted upon the operating stem of the main valve; and

Fig. 3 is a vertical sectional view of a modified form of the device.

The present device is well adapted for quantity manufacture as loose fits are permissible, no springs are required, none of the valves need to fit absolutely tight, and the main valve is held to its seat by air pressure, hence it tends always to seat firmly. In addition, the parts are so organized and constructed that the float and pilot valve mechanism assists the motor in its operation of actuating the main valve. The float and pilot valve mechanism also serves as positive means for closing the main valve and also the relief valve, if such is employed.

Referring now to Fig. 1, I have shown the vacuum tank as comprising an upper or pumping chamber 1 and a lower or reservoir chamber 2. The upper chamber 1 is defined by the top member 3, bottom member 4 and side wall member 5. The top and side wall members 3 and 5 are connected together by means of suitable flanges 6 and 7 which are preferably fastened by suitable screws 8. The reservoir 2 is defined by the cylindrical tank member 9 having the bottom 10 which has a suitable outlet 11 for supplying gasoline to the carburetor or other device which is fed from the reservoir 2. The tank 9 has a cylindrical flange 12 at its upper end which registers with the flanges 6 and 7 and is held thereto by means of a peripheral channel member 13, which holds the upper and lower tank together. A series of atmospheric openings 14 are formed in the upper side walls of the tank 9 to put the reservoir 2 in communication with atmosphere.

The side walls 5 of the upper tank or pumping chamber have inturned flanges, as indicated at 16, for connecting to the bottom 4. The bottom part 4 has a relatively large valve port 18 defined by a circular flange 19 which forms a seat for the dumping valve 20. This dumping valve 20 has an adjustable stem 21 threaded therethrough and locked by means of the lock nut 22. The

stem 21 is pivoted at 23 to the lever 24, which lever 24 in turn is pivoted at its center part 25 to the bottom wall 4 of the upper tank portion. The opposite arm of 5 the lever 24 is pivoted loosely, as indicated at 26 to the operating stem 27, which operating stem is secured at its upper end to the movable motor element 28, which in this case comprises a flexible metal dia- 10 phragm. The stem 27 is threaded at its upper end and the two clamping plate members 29 and 30 are threaded and locked upon opposite sides of the diaphragm 28 to the stem 27. After the diaphragm plates 29 15 and 30 are threaded upon opposite sides of the diaphragm 28 and secured to the stem 27, a hole is drilled therethrough and a short piece of tubing 31 is pressed thereinto, this piece of tubing depending as shown in the 20 drawing and forming a valve seat. The opening through the tube forms a passageway. The opening through the tube 31 is controlled by a disc valve 32 borne upon the upper end of the sleeve 33, which sleeve fits 25 loosely upon the operating stem 27. At its lower end the sleeve 33 is adapted to engage the adjacent end of the main valve operating lever 24. This sleeve has a flange 34 upon which the float 35 is adapted to rest when 30 the float is in its lowermost position. Thus the weight of the float and the valve sleeve 33 rests upon the adjacent end of the valve operating lever arm 24 to close the valve 20. The lost motion at the point of connection 35 between the stem 27 and the valve operating lever 24 permits the weight of the valve and float to close the main valve 20, independ- 40 ently of diaphragm 28.

The upper plate member 29 has upon its upper face a conical plug valve 36 which registers with the passageway 38 formed in the threaded sleeve 39. This threaded sleeve has a central passageway which communicates with the suction connection for 45 the tank. The pipe socket 40 is adapted to receive a suitable pipe connection running to the intake manifold of the engine for withdrawing air through the passageway 38. This threaded sleeve 39 may be moved up 50 or down, placed in proper position so that when the diaphragm 28 is raised to its uppermost position, the float member 36 will obstruct and substantially shut off communication between the source of suction and the motor chamber 41, which is formed between the top of the diaphragm 28 and the adjacent portion of the top 3. The dia- 55 phragm 28 is formed with suitably depending flanges fitting into a cylindrical housing 43 to which said depending flanges 42 are securely fastened, as by soldering the edges together.

The top member 3 has a suitable pipe socket 44 for connecting the gasoline supply 60 pipe, which gasoline supply pipe runs to

a suitable low level tank for providing gasoline or such other liquid as is to be pumped.

Fig. 2 shows how the sleeve 33 may be cut away to avoid the jamming of scale or dirt between the sleeve and the operating 70 stem 27. The float 35 should fit loosely upon the sleeve 33 so as to be guided freely up and down along said sleeve from high to low level and reverse.

The operation of the device shown in Fig. 75 1 is as follows:—Assuming that the parts are in the condition shown and that the socket 40 is suitably connected to suction and the socket 44 suitably connected to a low level supply tank for drawing liquid. The weight 80 of the float and pilot valve closes the main valve 20. Suction enters through the passageway 39 and through the valve port in the pipe 31. As soon as suction enters the chamber 1 the valve 20 is immediately held 85 to its seat by the difference in pressure between the inside of the chamber and atmosphere. As liquid fills the chamber the float 35 rises along the sleeve 33 until the chamber is substantially full, whereupon the float 90 35 lifts the valve disc 32 and its connected sleeve 33 into contact with the end of the tube 31, thereby closing off the suction connection to the interior of the chamber 1. Upon further withdrawal of air from the 95 motor chamber 41, the valve disc 32 tends to be held upon the end of the tube 31 by suction, and at the same time the difference in pressure upon the two sides of the dia- 100 phragm 28 causes said motor member to rise, pulling upward upon the adjacent end of the lever 24 and thrusting down the valve 20 to open it against the pressure of atmosphere which tends to hold it closed. Immediately 105 the contents of the pumping chamber 1 begin to discharge and air begins to enter the large opening 18 so that the liquid contents is quickly dumped. It will be noted that there is no means other than the valve 20 for admitting air, and that this valve therefore 110 not only controls the admission of air, but also the dumping of liquid.

As the liquid contents fall, the float 35 is guided downwardly along the stem 33, but the suction of the engine operating through the opening in the tube 31 upon the disc 32 holds said disc against said opening until the float descends against the flange 34. The weight of the float in addition to its oscillating motion as it rises and falls, due to the bubbling of air through the liquid causes the valve 32 to be pulled from its seat against the tube 31 and to descend against the adjacent end of the arm 24 causing it to close the valve 20 at substantially the same time that the suction connection 31 is opened.

The obstruction of the passageway 38 by the valve 36 is not essential, as these parts may be so proportioned that the opening of the passageway 31 will at once sufficiently 130

- relieve the difference in pressure upon the diaphragm 28 to cause it to descend to such a point as will permit the float and connected parts to substantially close the valve 20 where it will be sucked or drawn to its seat by lowering of pressure in the pumping chamber 1. I prefer to use the valve 36, since by so doing the connection from suction to the valve chamber 41 is so greatly reduced that the air entering through the passageway in the tube 31 will quickly reduce the pressure in said chamber 41 to such a point as to permit the diaphragm 28 to descend.
- 15 As shown in Fig. 3 I have provided a flat disc valve 36' adapted to seat against the lower end of the tube 38 so that this flat disc valve may be held fairly tight against the valve port on the end of the nipple 39 to permit equalization in pressures upon opposite sides of the diaphragm 28 to quite a degree before suction is again connected through the diaphragm chamber 41 and the pumping chamber 1.
- 20 I have also shown the valve seat which is formed upon the lower diaphragm plate 30' as being formed by an annular groove 46 which gives a relatively large area cooperating with the valve plate or disc 32' which is mounted upon the upper end of the stem or sleeve 33'. In the present case, instead of having a traveling float, I have provided two floats, namely, a high level float 47 and a low level float 48, which are secured upon said sleeve 33'. The buoyancy of the float 48 is substantially sufficient to equal the weight of the valve and stem 32', 33' and the upper float 47, so that when the liquid reaches the upper float 47, said float is effective to apply the valve 32' to its seat. The weight of the two floats 47 and 48 with their connected parts is sufficient to close the valve, which in this case consist of a main valve member 20' and a relief valve 50, which is provided with a conical seat facing a similar conical seat 51 formed in the central part of the main valve 20'. The stem 21' is attached to said conical relief valve 50 and is locked thereto by a nut 22'. The stem 21' is threaded through a passageway 52 in the main valve 20', so that when the motor diaphragm 28 rises and pulls on the stem 27, the lever 24 thrusts the stem 21' down, first opening the relief valve 51 and then thrusting down the main valve 20'. The employment of this relief valve insures a pressure differential being secured upon diaphragm 28 adequate to thrust down the main valve 20' against atmospheric pressure on the outside. The relief valve 50 may be made of sufficient size so that opening thereof will quickly unbalance the motor 28 and cause rapid operation of the entire valve mechanism.
- 25 The pivot 25 for the lever 24 is mounted upon a stem 54 which projects through the bottom 4' and has a projecting washer 55 held in place by lock nut 56. This collar 55 projects below the adjacent edge of the valve member 20' to cause it to tilt to assist in washing off sediment and to control the action of the discharging liquid.
- With the modifications above noted, the operation of this form is fundamentally the same as the preferred form previously described.
- It will be noted that the float mechanism assists instead of opposes the action of the main motor. Since the main valve is large in area, sufficient opening may be gained by a relatively minute travel of the diaphragm member 28. The float required is small, since its sole work consists in lifting the valve disc 32 to seat, the motor and the suction doing the rest of the work. The valves are all opened and closed with a snap without the use of a single spring.
- I do not intend to be limited to the details shown or described, except as the same appear in the appended claims.
- I claim:
1. In a device of the class described, a chamber having a liquid inlet, a combined liquid outlet and air inlet, a suction connection and a motor operated by suction from said connection upon high level in the chamber for opening the combined liquid outlet and air inlet.
  2. In a device of the class described, a pumping chamber having a liquid inlet, a suction connection, a motor between said suction connection and the chamber, an exhaust valve for admitting atmosphere, a float for applying said valve to its seat when the chamber is substantially empty and a high level controlled valve for causing the motor to open said atmospheric valve when liquid has filled the pumping chamber.
  3. In combination, a pumping chamber having a liquid admission connection, a suction connection and an air admission port in the bottom of said chamber, an air admission valve seating with pressure and adapted to be applied to seat when the chamber is substantially empty, and a motor having its motor element constantly exposed on one side to the pressure in the chamber and controlled by a high level of liquid in the chamber for opening said valve against pressure.
  4. In a device of the class described, a pumping chamber having a bottom wall, an air admission port through the bottom wall, an air admission valve of the lift type seating with pressure upon said port, a fluid pressure motor for lifting said valve from its seat, and a high level responsive pilot valve for said motor for controlling said motor to open said air admission valve.
  5. In a device of the class described, the

- combination with a pumping chamber provided with a liquid admission connection and an air inlet and liquid discharge valve port, of a poppet valve adapted to close said port
- 5 5 when the chamber is substantially empty and being adapted to be retained closed by the difference between the pressures in the pumping chamber and the outside thereof, a suction admission valve, a fluid actuated
- 10 motor for opening said poppet valve, and means for closing the suction admission valve and causing the motor to open the exhaust valve when the liquid has substantially filled the pumping chamber.
- 15 6. In a vacuum tank, a closed pumping chamber, a vacuum chamber, a motor member between said chambers, a port opening between said chambers, a dump valve for the pumping chamber, an operating connection between said motor member and said dumping valve, and a float operated pilot valve controlling said port and being guided upon said operating connection.
- 20 7. In a vacuum tank, a closed pumping chamber, a dumping valve therefor seating with atmospheric pressure, a motor chamber, a motor member between said chambers, a valve passageway between said chambers, a level controlled valve for obstructing said valve passageway and causing the motor member to open the dumping valve.
- 25 8. In a vacuum tank, a closed pumping chamber, a dump valve therefor, a fluid pressure operated motor for opening said dump valve, a level controlled device for pneumatically governing said motor and for mechanically closing said valve.
- 30 9. In a device of the class described, a closed pumping chamber, a motor chamber, a diaphragm between said chambers, a passageway between said chambers, a dump valve for the pumping chamber, a stem connecting the diaphragm and the dump valve, a pilot valve guided on said stem and a float for said pilot valve.
- 35 10. In combination, a pumping chamber, a dumping valve therefor, said valve seating with atmospheric pressure, a motor chamber having a motor member exposed on one side to the interior of the pumping chamber connected to said dumping valve, level controlled means for applying said pumping valve to its seat and for governing the effective application of suction to said motor member for opening said dumping valve.
- 40 11. A vacuum tank having a suction chamber, said chamber having a top wall member including a suction connection, a motor chamber formed below said suction connection, said motor chamber having a flexible wall forming a motor element, an

adjustable valve seat member forming a connection between the suction connection and said motor chamber, a valve member carried by said diaphragm for obstructing the 65 passageway through said adjustable member, a stem secured to the diaphragm, a passageway formed through the diaphragm, said passageway terminating in a valve port, and a pilot valve guided on said stem and controlling said valve port.

12. In a device of the class described, the combination of a pumping chamber provided with a liquid admission connection, and a combined air inlet and liquid discharge 75 valve port, of a poppet valve adapted to close said port when the chamber is substantially empty and being adapted to be retained closed by the difference between the pressures in the pumping chamber and the 80 outside thereof, a relief valve, a fluid actuated motor for opening said relief valve when the liquid has substantially filled the pumping chamber to equalize the pressure in said fluid chamber and the outside there- 85 of.

13. In a device of the class described, a pumping chamber having a liquid inlet, a suction connection and a combined liquid outlet and air inlet, a compound poppet valve closing said last named valve port, a suction operated motor for opening said compound valve, and level controlled means for applying said compound valve to its valve port when the chamber is substantially 95 empty and for controlling the motor to open said compound valve when the chamber is substantially filled with liquid.

14. In combination, a pumping chamber having a top wall, a motor chamber mounted 100 on said top wall of the pumping chamber, a motor element between the chambers, a downwardly extending stem connected to the motor element, a dumping valve having a port in the bottom of the pumping chamber, 105 a lever connecting the valve and the stem, and a float on the stem for closing the valve and controlling the effective application of suction to the motor.

15. In combination, a pumping chamber, 110 a motor chamber, a flexible diaphragm between them, a pair of plates on opposite sides of the diaphragm, a stem connected to said plates, a passageway through said plates and said diaphragm, a dumping valve for 115 the bottom of the pumping chamber connected to said stem, and a level control valve guided on said stem and controlling said passageway.

In witness whereof, I hereunto subscribe 120 my name this 23rd day of Oct., 1923.

JOHN A. DIENNER.
